WILLIAM HAAS
INVENTOR
BY Thomas J. Wallace
ATTORNEY

UNITED STATES PATENT OFFICE

130,775

DESIGN FOR A BUTTON OR SIMILAR ARTICLE

William Haas, New York, N. Y.

Application November 19, 1941, Serial No. 104,205

Term of patent 3½ years

To all whom it may concern:

Be it known that I, William Haas, a citizen of the United States of America, residing in New York city, county of New York, and State of New York, have invented a new, original, and ornamental Design for a Button or Similar Article, of which the following is a specification, reference being had to the accompanying drawing, forming part thereof, wherein,

I claim:

The ornamental design for a button or similar article, substantially as shown.

WILLIAM HAAS.
